[57] CLAIM

The ornamental design for a jet ski lift for a trailer, as shown and described.

DESCRIPTION

FIG. 1 is a perspective view of a jet ski lift for a trailer showing my new design;

FIG. 2 is a front elevational view thereof;

FIG. 3 is a rear elevational view thereof;

FIG. 4 is a left side elevational view, with the right side being a mirror image thereof;

FIG. 5 is a bottom plan view thereof;

FIG. 6 is a top plan view thereof;
FIG. 7 is an environmental, side elevational view thereof, showing the lift fully raised, a jet ski supported thereon; and, FIG. 8 is an environmental, side elevational view thereof, showing the lift partially raised.

The broken line showing of a trailer, a boat, and a jet ski in FIGS. 7 and 8 is for illustrative purposes only and forms no part of the claimed design.

The contrasting cross-hatched shading shown on FIGS. 1-6 represents a cloth surface and is understood to cover the entire surface.
